UNITED STATES PATENT OFFICE

CLAYTON TRIDLE ULREY, OF EAST ORANGE, NEW JERSEY, ASSIGNOR TO WESTINGHOUSE LAMP COMPANY, A CORPORATION OF PENNSYLVANIA

MANUFACTURE OF ELECTRON-EMITTING DEVICES AND THE LIKE

Application filed July 24, 1922. Serial No. 577,021.

This invention relates to the manufacture of electron-emitting devices and the like and more particularly to the use of thorium to sensitize and activate electron-emitting cathodes and as a clean-up agent.

5 An object of my invention is the preparation of a refractory filament coated with thorium by vaporization from a mass of thorium.

10 Another object of my invention is the manufacture of radio bulbs, X-ray tubes or the like, each having a plate or target consisting of thorium, in whole or in part, whereby the electron-emitting element or filament may 15 be sensitized and activated therefrom initially and whereby such activation may be repeated as often as may be necessary or desirable.

15 A further object of my invention is the production of electron-emitting devices, each with a plate therein composed, at least partly, of thorium whereby the same may be utilized for coating the electron-emitting filament with thorium by vaporization or 25 sputtering therefrom, under the influence of heat or electronic bombardment, to increase its electron-emissivity and, at the same time, acting as a clean-up agent for improving the vacuum in the bulb.

30 A still further object of my invention is the manufacture of radio bulbs, X-ray tubes and other electron-emitting devices, in which the hot-cathode is composed principally of a filament of tungsten or the like and is 35 adapted to operate at a much lower temperature than pure uncoated tungsten and still develop the requisite electron-emission, because of the application thereon, by distillation from a component part of the device, of 40 a coating of material of large electron-emissivity.

Other objects and advantages will be apparent upon reading the following description.

45 In electron-emitting devices such as radio bulbs, X-ray tubes and the like, it is desirable to have the hot-cathode or electron-emitting element thereof composed of a material having a high thermionic electronic-emissivity. Experiments have shown that, of

materials suitable for this purpose, thorium has a high value but it also has a lower melting point than tungsten and molybdenum and there is considerable difficulty in producing it in filamentary form. It oxidizes 55 readily when so produced and hence is not well adapted for electron-emitting material in the pure, metallic form if not combined or consolidated with other materials. Because of these properties of thorium, various 60 attempts have been made to use it consolidated with, or attached to, other more refractory metals, such as tungsten.

In Patent #1,244,216, October 23, 1917, Langmuir describes a method of heat-treating thoriated tungsten filament to develop a film of thorium thereon. The process described in the patent is a delicate one and, apparently, has to be closely followed to obtain the desired result for it is stated on 70 page 2, lines 105 to 109, of said patent that, if a trace of oxygen is admitted to the bulb, the electron-emission immediately falls as low as, or even lower than, the low value observed when a cathode of pure tungsten is 75 slightly oxidized.

In Patent #1,244,217, October 23, 1917, Langmuir describes a method of developing a surface coating of thorium on a thoriated tungsten filament by reduction of some of 80 the thoria in the filament, which is more or less difficult to practice, and the results obtained are not as good as that from pure thorium.

According to my invention, I have avoided 85 the defects of the prior art by mounting an electron-emitting cathode adjacent to a plate or target consisting, at least in part, of thorium. The cathode, preferably in filamentary form, may comprise a refractory metal, 90 such as tungsten, and the same is sensitized or activated, that is, the electron-emissivity thereof is increased to that of thorium by depositing thereon a film or coating of thorium from the plate or target, when used for 95 an X-ray tube, by heating said plate or the like to incandescence to vaporize or sputter therefrom the requisite amount of thorium to deposit the same on the filamentary cathode.

The process is preferably carried out by 100

energizing the cathode to an electron-emitting temperature from a suitable source of electricity and then impressing a high potential between said cathode and the plate, thereby heating the plate to incandescence by electron-bombardment. Such treatment causes partial vaporization of the thorium of the plate which will exert a clean-up action on residual gases, if any, in the bulb, and a film of metallic thorium will condense and will be deposited on the surface of the heated filamentary cathode, under the directing influence of the potential between the cathode and the anode or plate.

15 My invention will better be understood by referring to the accompanying drawing, in which, an electron tube or radio device, as one embodiment of my invention, is illustrated in side elevation, partly in section, 20 and diagrammatically shown connected for sensitization or activation thereof.

The radio device 1 may comprise an evacuated sealed envelope or bulb 2, a filamentary cathode or electron-emitting element 3, 25 a grid 4 and an anode or plate 5. Extending through the press 8 are leading-in wires 6 and 7 for the energization of the filament 3. Leading-in wires 9 and 11 also extend through the press 8 to make electrical connection to the grid 4 and the plate 5, respectively.

The plate 5 may be composed entirely of metallic thorium or may comprise a plate of tungsten or molybdenum painted with powdered thorium metal in a suitable binder, but it preferably consists merely of a plate of tungsten or molybdenum with a strip or clip of thorium metal attached thereto, as represented at 12.

40 The thorium may be prepared in powdered form by the calcium-reduction process or by the process described and claimed in the application of John W. Marden, Serial Number 432,324, filed December 21, 1920,

45 Preparation of rare metals, and assigned to the Westinghouse Lamp Company. If a plate of clip of thorium is to be used, the metal may be sintered and fused into a coherent mass by the method described and 50 claimed in the application of John W. Marden et al., Serial Number 432,325, filed December 21, 1920, Sintering and fusing of metal powders into coherent metals, and assigned to the Westinghouse Lamp Company.

55 The furnace used for such sintering and fusing may be that described and claimed in the application of Harvey C. Rentschler, Serial Number 430,118, filed December 13, 1920, Furnaces, and assigned to the Westing-

50 house Lamp Company.

The grid 4 may be a coil of tungsten or molybdenum wire. The filament 3 may be composed of refractory metal such as tungsten, molybdenum or the like.

55 The bulb 2 may be exhausted in the usual

manner after which the filament 3 is activated for the purpose of increasing its electron-emissivity to that of pure thorium by the following method. The filament 3 is energized from a battery 13 or other suitable source of electricity by closing the switch 14, whereby it becomes heated to an electron-emitting temperature. A high potential may then be established between the filament 3 and the plate 5 by closing the switch 15 to energize the primary 16 of the adjustable transformer 17 from a suitable source of alternating current, such as a single-phase generator 18. This causes energization of the secondary winding 19 of the transformer 17 and, as said winding is connected to leading-in wires 6 and 11, a high potential is thereby established between the filament 3 and the plate 5. This causes the plate 5 to become heated on account of the electron-bombardment from the filament to a temperature sufficient to effect the distillation or vaporization of thorium metal, that is, to about 2000° C. If desired, the plate 5 may be heated inductively by surrounding the device by a coil and passing high-frequency current through the same. This will make the plate 5 a secondary of the coil and heat the plate by means of the current induced therein.

The degree of heating of the plate may be regulated by adjusting the impressed potential from the transformer 17 or by regulating the temperature of the energized filament 3 by adjusting the rheostat 21 in circuit therewith. The activation of the filament 3 by vaporization or sputtering from the plate 5 or the strip of thorium 12 attached thereto may be determined by noting the amount of the thermionic current registered on the milliammeter 22 with the potential of the secondary 19 reduced until the plate is cold, the filament still being energized. After the requisite increase has occurred in the current registered by the milliammeter 22, for a certain potential between the filament and the plate, the filament 3 will then be sufficiently activated, because of the film or coating of thorium deposited thereon from the plate 5 or strip of thorium 12 attached thereto.

The device 1 may then be utilized for the purpose desired, as, for instance, radio work. The filament 3 will be found to have the same electron-emissivity at a temperature of about 1600° K. as pure tungsten at about 2000° K. If, at any time, it is noted that the electron-emissivity of the filament 3 drops because of over-heating of the same or for any other similar reason, the aforescribed process of activation may be repeated and the filament 3 be again activated to its former electron-emissivity.

Although the aforescribed process of activating filaments is primarily designed

to increase the electron-emissivity thereof, it will be found that such treatment will efficiently clean-up residual gases in the bulb because of the efficient clean-up action of highly heated or vaporized thorium. This clean-up action may be repeated in the same way in which the activation of the filament is repeated.

It will be apparent that, according to my improved process for activating an electron-emitting filament, the film of thorium deposited thereon will tend to adhere thereto in a very efficient manner, because the filament is heated during the process of distillation. For this reason, the surface coating of thorium is not only firmly attached to the filament but may even form a superficial alloy therewith. The distillation of the thorium by this method is also more efficient because of the directive influence of the potential difference between the filament and the plate, during the distillation of the thorium to the filament, that is, the charged particles of thorium distilled from the plate will be drawn to the filament and condensed thereon rather than be distilled uniformly to all adjacent parts of the device.

On account of providing a relatively large mass of thorium in the electron device, the activation of the filament may be repeated a large number of times and, for this reason, the efficiency of the device for electron-emission may be maintained for an indefinite period. For this same reason, the thorium may be used simultaneously as a clean-up agent because there is a surplus provided beyond that needed for activating the filament.

Although I have described what I consider the preferred means of practicing my invention and have shown a preferred embodiment thereof, it is to be understood that the same are merely illustrative and that my invention is limited only by the spirit and scope of the appended claims.

What is claimed is:

1. The method of activating a refractory incandescent cathode for electron emission purposes, comprising enclosing the same in an evacuated envelope with another electrode consisting at least in part of thorium metal and heating the said electrode by electron bombardment to a temperature sufficiently high to partially vaporize said thorium and sputtering said vaporized thorium from said electrode to the cathode.

2. The method of activating a refractory incandescent cathode for electron emission purposes comprising enclosing the same in an evacuated envelope with another electrode consisting at least in part of thorium and impressing a high voltage discharge between the cathode and other electrode to heat the electrode to a sufficiently high temperature to partially vaporize said thorium and sputter-

ing the vaporized thorium on to said cathode.

In testimony whereof, I have hereunto subscribed my name this 21st day of July, 1922.

CLAYTON TRIDLE ULREY.
